UNITED STATES PATENT OFFICE.

PAUL RICHERT, OF BERLIN, GERMANY.

TAXAMETER OR FARE-INDICATOR FOR HIRED VEHICLES.

No. 907,404.

Specification of Letters Patent.

Patented Dec. 22, 1908.

Application filed April 27, 1908. Serial No. 429,335.

To all whom it may concern:

Be it known that I, PAUL RICHERT, a citizen of the German Empire, residing at Berlin, in the Kingdom of Prussia, German Empire, have invented new and useful Improvements in Taxameters or Fare-Indicators for Hired Vehicles, of which the following is a specification.

My invention relates to taxameters or fare indicators for hired vehicles, and its objects are to enable the same to be operated with the least possible loss of time, particularly at the beginning and end of the journey, to provide protection against certain fraudulent manipulations of the driver and to attain further advantages as regards the construction and applicability of the apparatus.

The persons who use a hired public vehicle have generally little time to spare. They require the driver to start at once, nor do they wish to be detained at the end of the journey. The driver who desires to comply with the wishes of his fare in this respect and has at the same time to keep his eye on the traffic and look after his horse or motor must be in a position to manipulate the apparatus quickly and conveniently.

The apparatus were previously so constructed that in order to set and alter them it was necessary to operate both the signal flag or device (hereinafter called the signal) and a setting or altering spindle, separate and distinct from the signal, it being only possible for the movements of the signal and spindle to take place in a certain sequence in consequence of the one being locked by the other. This arrangement affords great protection against fraudulent manipulation of the totalizing mechanism which registers the number of journeys or fares and consequently the number or total sum of the initial fares received. This mechanism, like the other adding mechanisms of the taximeter, has no end position, but begins to count from zero again after its highest indication (999 for example) has been reached. If it were not for the locking arrangement before mentioned, the driver could move this totalizing mechanism through zero to any figure in a relatively short time by repeatedly putting the apparatus into operative condition. But the locking of the two devices used for setting and altering the apparatus involves tedious or complicated manipulation. The practice was therefore afterwards adopted for transferring to one device, viz. the signal, the

whole duty of setting the apparatus into and out of operative condition and to the various working conditions.

In setting the apparatus for the various conditions of service, for example, from "Free" to "Tariff 1", "Tariff 2", "Tariff 3", "Cash" and back to "Free" the signal was turned round through 360°. This arrangement presented the advantage that it allowed of ready manipulation in setting the apparatus for use. The taxameter could be set for service by simply lowering the flag and without the operation of a second device. The arrangement, however, possesses very considerable disadvantages. In the first place it is possible to fraudulently move the above mentioned totalizing mechanism through zero to any figure in a relatively short time by repeatedly turning the signal round. It is a further disadvantage that the signal has to be turned through a complete revolution every time to bring the apparatus back to "Free". If for example a three tariff apparatus is set for "Tariff 1" it is necessary to turn the signal through "Tariff 2" "Tariff 3" and "Cash" to bring it to "Free" position. This disadvantage of having to put the signal to positions corresponding to conditions of hire (in the present case "Tariff 2" and "Tariff 3") which have nothing to do with the particular journey, in order to set the apparatus to "Free" might be avoided if the apparatus were put into the "Free" position by simply turning the signal back, instead of turning it right round in the forward direction. With such an arrangement it would not be necessary in the above example of an apparatus set for "Tariff 1" (which is the most usual case), to move the apparatus through "Tariff 2" and "Tariff 3" in order to bring it to "Free". But here a new difficulty arises. It has been found desirable to provide for an intermediate position between the various working positions and the "Free" position, namely the so-called "Cash" position, to which the apparatus is set at the end of the journey when the fare is to be paid by the passenger. In setting the apparatus to this position the clockwork driving mechanism is generally thrown out of operation (for example by stopping the balance wheel) in order that the amount of the fare shall not increase during the time occupied in payment, which might lead to differences between the passenger and driver and to trouble for the driver with the cab proprietor. On the

other hand the distance drive generally and properly remains in engagement while the apparatus is set to "Cash", so that if the vehicle is driven further with the apparatus in 5 this position the fare indicated is increased. In taximeters as previously constructed the setting to "Cash" is effected by means of the same device (for example the signal) as that which serves for setting the apparatus to the 10 other working positions. Consequently the "Cash" position must be arranged immediately before the "Free" position. The arrangement is then such that the apparatus cannot be set back from "Cash" to a tariff 15 position. This "Cash" position involves difficulties when it is desired to construct an instrument capable of being set to operative position and for the various tariffs by turning the signal in one direction and to the "Free" 20 position by turning the signal back, which arrangement would present the above-mentioned advantages.

With the "Cash" setting arrangement hitherto employed, the "Cash" position 25 would, even in such an apparatus, have to be necessarily arranged immediately before the "Free" position, and consequently in returning the signal this would have to be put first to "Cash" and then to "Free", to prevent its being possible or necessary to set 30 the apparatus from "Cash" to a tariff before putting it into the "Free" position, and in order that the indication "Cash", *i.e.* the indication of the completion of the journey, 35 should not be thus again canceled. The consequence would be that the "Cash" position would have to be passed through in turning the signal forward from "Free" to a tariff. But the setting of the apparatus to 40 "Cash" before the commencement of the journey is absurd and would under some conditions lend itself to fraud. In order therefore to effect the setting, altering and putting out of operation of the apparatus by turning 45 the signal forward and back, the method previously employed for setting the apparatus to "Cash" must be abandoned in order to prevent the disadvantage mentioned. The system previously employed 50 for this purpose possesses further defects. In particular it does not allow of setting the apparatus to "Cash" quickly enough at the end of the journey. For example at the end of a journey on "Tariff 1," the apparatus 55 (assuming it to be of the type in which the signal is turned through a complete revolution) can only be set to "Cash" through "Tariff 2" and "Tariff 3". These manipulations cannot be performed so quickly and 60 certainly as could be desired by a chauffeur who has to look after a number of levers or a driver engaged in holding in a restive horse in a crowded thoroughfare. Similarly, with an apparatus which is set by turning the 65 signal forward and is put out of operative

position by turning the signal backwards, it would be necessary, at the end of a journey on "Tariff 3," to put the apparatus back to "Tariff 2" and "Tariff 1" before it could be set to the "Cash" position. A further disadvantage of the previous systems of setting to "Cash" is that when the apparatus has been put to this position the passenger can no longer see for what tariff it was previously set. 75

It is the driver's right and duty at the end of the journey to put the apparatus to the "Cash" position. But in many cases the passenger never looks at the apparatus, to see the amount of the fare and the tariff on 80 which he has been driven, until this moment. With the arrangements hitherto employed, the indication of the tariff for which the apparatus was set disappears when the apparatus is moved to the "Cash" position, so 85 that the passenger can no longer see whether the driver had set the apparatus to an excessive tariff or not. Finally it is a great disadvantage that the "Cash" indicating arrangement is not sufficiently distinguished 90 from the various tariff indicating arrangements, since the payment is indicated by the same means and at the same place as the tariffs. Consequently it is possible for a driver who has just put down a fare and taken 95 up another one—say a foreigner, whom he thinks he can cheat—to drive on with the apparatus at "Cash". In this way he cheats the second fare, who has to pay the amount of the previous journey again, and 100 also the owner of the vehicle to whom he has not to pay the amount of the first journey.

By means of the present invention all disadvantages and possibilities of fraud are avoided. 105

The drawing illustrates by way of example one form of a taximeter constructed to embody the invention, all parts to which it is unnecessary to refer being omitted.

Figure 1 is a sectional elevation on line 110 A—A, Fig. 2, with the parts in the "Free" position. Fig. 2 is a corresponding plan view, in section on line B—B, Fig. 1. Fig. 3 is a similar elevation to Fig. 1 with the apparatus set for "Tariff 1". Fig. 4 is a similar 115 elevation with the apparatus set to "Cash". Fig. 5 is a front elevation of the apparatus set to "Cash", drawn to a reduced scale.

a is the casing of the apparatus closed at front by a glass window *b* and at the rear by 120 a back *c* screwed to the casing.

d is the spindle of the signal *e* rotatably mounted in the back *c*.

On the spindle *d* is fixed a wheel *f* formed with gaps in its periphery. A strong spring *g* tends to keep a roller *i* pivotally mounted on a lever *h*, pressed against the wheel *f* and to hold the spindle *d* in one of the positions in which the roller *i* is seated in a gap of the wheel *f*. On the spindle *d* is likewise secured 125 130

a disk k carrying a number of pins k^1 . These pins serve to rotate a star wheel l , which in the example illustrated is in the form of a five-pointed star.

5 l^1 is a lever pressed by a spring l^2 between two arms of the star wheel and serving to hold it in its proper positions. The spindle l^3 of the wheel l is mounted in the frame plates m^1 m^2 and carries one or more cams l^4 10 that actuate the levers (not shown) which serve for putting the apparatus into the operative and disengaged positions and also a disk l^5 bearing the desired indications such for example as "Tariff 1" or "2", "3", 15 "Free" which are displayed through an aperture in the front frame plate m^3 .

To the disk k at a part of its circumference is secured a segmental metal piece formed at its outer edge with ratchet teeth k^2 and at 20 its inner edge with oppositely directed ratchet teeth k^3 .

25 n is a tooth or nose fixed on a lever n^2 pivoting about n^1 , this tooth being adapted to engage the outer teeth k^2 or the inner teeth k^3 , according to the position of lever n^2 , as described later.

30 n^3 is a strong flat spring which presses against a flat portion of the lever n^2 and tends to return this lever to the desired position 35 when it has been turned in either direction out of this position.

With the improved taximeter, the apparatus is only set to operative position to the 40 various tariffs and to the "Free" position by the signal, the setting to "Cash" being effected by a separate device. In the example 45 illustrated the setting to a tariff is effected by turning the signal in the one direction, and the setting to the "Free" position by turning the signal back. By this means the above 50 mentioned advantage is attained that after a journey on "Tariff 1", which is the most usual case, there is no necessity to move the apparatus to "Tariff 2" and "Tariff 3", but 55 it can be at once put back from "Tariff 1" to "Free".

A further advantage is however attained. The backward rotation of the signal to "Free" is limited by the stop pin e^1 (see Figs. 55 1 and 2), the forward rotation by the stop pin e^2 . The angle through which the signal can be turned forward may be varied by changing the position of the pin e^2 , and by this means the number of positions or conditions of hire to which the apparatus can be 60 set may be varied. With the pin e^2 in the position shown two different settings are possible, for example to "Tariff 1" and "Tariff 2". By changing the position of the pin e^2 , 65 this two-tariff apparatus can be converted into an apparatus for a different number of tariffs or working conditions, for example into a one-tariff, three-tariff, or four-tariff apparatus. This is of great advantage, both 70 as regards the manufacture of the apparatus

and its ready interchangeability, as the tariffs vary in different cities and moreover are frequently changed in consequence of police regulations.

In setting the taximeter from "Free" to 70 "Tariff 1", that is to say in turning the signal e from the position shown in Fig. 1 to that shown in Fig. 3, the tooth n engages the ratchet teeth k^3 . In moving the taximeter from "Tariff 1" to "Free", that is to say in 75 turning the signal e back from the position Fig. 3 to that in Fig. 1, the tooth n comes into engagement with the oppositely directed ratchet teeth k^2 . Consequently in setting to "Tariff 1" the driver cannot move the signal 80 back from an intermediate position to "Free", but can only continue to turn the signal down. Similarly in setting to "Free" the driver cannot set the signal on again to "Tariff 1" from an intermediate position but 85 can only continue to turn the signal back. There is no obstruction in either direction of rotation between the different tariffs ("Tariff 1" and "Tariff 2" in the example 90 illustrated), and consequently the apparatus can be set backwards and forwards at will between the different tariffs.

According to the present invention the setting of the apparatus to "Cash" is not effected by the same device as that which 95 serves for the other conditions of hire (in the example illustrated the signal) but by a separate device, and it is not indicated at the same place or by the same means (disk l^5) as the other conditions of hire, but at 100 another point and by means of a distinct device, namely a long flap q^2 which is caused to drop obliquely in front of the frame plate m^3 visible at the front of the apparatus and formed with an aperture for exposing the 105 tariff disk l^5 and an aperture s for exposing the amount of the fare indicated by the apparatus. The flap q^3 is preferably of a striking color, bright red for example, and should bear a distinctly legible inscription, such as 110 "End of journey—cash".

The flap q^2 can be at once displayed with any desired tariff (both "Tariff 1" and "Tariff 2" in the example illustrated) by slightly turning a knob. The amount of 115 the fare and the tariff both remain indicated. The flap can only be caused to disappear by putting the apparatus to "Free".

The dropping of the special flap q^2 with its inscription announcing the end of the 120 journey and requesting payment to be made, alters the face of the instrument so strikingly as compared with its appearance when set to a tariff that no driver would venture to take up a new fare and drive on without 125 first returning the flap q^2 out of sight by putting the apparatus to the "Free" position and setting it anew. This obviates the possibility of fraud which can be committed with all apparatus in which "Cash" is 130

indicated by the same means and at the same point as the various tariffs.

The fact that the flap q^3 can be at once displayed with any desired tariff presents two further advantages of great importance in practical use. Firstly the direct operation of the device by a small knob can be much more readily and quickly done than is possible when the apparatus has to be effected by moving a more difficultly manipulated setting device, the signal for example, through a number of other working positions such as "Tariff 2" and "Tariff 3". The importance of this easy and quick operation has been shown above. Further the tariff to which the apparatus was set remains visible after the flap has been displayed. The importance of this fact has also been referred to above. The driver is also compelled to display the flap q^3 , as the signal is prevented by suitable means from being put to "Free" until the flap has been set. Thus the further advantage above mentioned is attained, namely that the so called "journey recorder" cannot be fraudulently moved to any desired indication in a relatively short time by moving the signal to and fro, inasmuch as the flap q^3 must always be operated in order to return the signal and consequently the moving to and fro of the signal must always be interrupted by the operation of another device. The same advantage is therefore attained as with apparatus in which the setting to the different working positions is effected by means of two devices such for example as the signal and a setting spindle operated by a separate handle. But as compared with the last mentioned kind of apparatus, both the setting to a tariff at the beginning of a journey and to "Cash" at the end of a journey can be more easily and directly effected.

The means by which the said advantages are attained are as follows in the example illustrated:—The flap q^3 is secured on a spindle q mounted to turn in the frame plates m^1 and m^2 . To the other end of the spindle q is attached a lever q^1 carrying a pin q^2 . A spring q^4 tends to keep the lever q^1 pressed down as far as permitted by the pin q^2 which bears against the arm p^1 of a lever p . In the position shown in Fig. 1 the lever q^1 and flap q^3 are raised, in which position the flap q^3 is covered by the projecting edge a^1 of the casing a (see Figs. 2 and 5). In this position the lever q^1 is held against the action of the spring q^4 owing to the arm p^1 of the lever p being correspondingly raised. The lever p carries a pin p^3 against which a stop on the disk k bears in the "Free" position (Fig. 1). In the example illustrated this stop is constituted by the metal piece in which the teeth k^2 and k^3 are formed. In this position of the lever p the left arm p^1 holds

the pin q^2 , lever q^1 , and flap q^3 in the raised position shown. Below the arm p^1 is the nose o^4 of a rotatable disk o^1 adapted to be turned against the pull of a spring o^2 by a knob o outside the back c . When the knob o is released, the disk o^1 is pulled by the spring o^2 into the position shown in Fig. 1, in which it bears against a stop o^3 . The right arm p^2 of the lever p bears upon a pin n^4 on the lever n^2 and thereby presses the lever n^2 down against the action of the flat spring n^3 to such an extent that the tooth n is level with the ratchet teeth k^3 . If now the flag is turned to the right from the position shown in Fig. 1, the tooth n slides on the ratchet teeth k^3 and prevents the flag from being raised again. In the position shown in Fig. 3, which corresponds to the setting for "Tariff 1", the tooth n has so far left the ratchet teeth k^3 as to be opposite the last tooth k^3 . The flat spring n^3 is tending to raise the tooth n to bring it opposite the teeth k^2 , but this lifting of the tooth n is prevented by the pin n^4 bearing against the arm p^2 and the arm p^1 bearing upon the nose o^4 of the disk o^1 . In this position therefore the tooth n prevents backward rotation of the disk k and consequently the possibility of turning the signal e back to "Free." To allow of this being done the nose o^4 must first be turned to the left by means of the knob o , so that the lever p , which through the medium of the pins n^4 and q^2 is subject to the action of the springs n^3 and q^4 , both tending to turn it in the same direction, can move down with its arm p^1 in front of the nose o^4 . This motion brings the flap q^3 into the position shown in Figs. 4 and 5. At the same time the balance wheel r of the clockwork is stopped by the rotation of the spindle q , through the medium of the flat spring q^5 attached to the spindle q , so that the amount of the fare cannot now be increased by the clockwork mechanism, but only by the distance mechanism. In this position of the lever q the lever n^2 is free to obey the action of the flat spring n^3 and it therefore moves into the position shown in Fig. 4, in which the tooth n is opposite the ratchet teeth k^2 . The signal can now be turned back into the position shown in Fig. 1 ("Free"), as the ratchet teeth k^3 allow of its return and only prevent the possibility of the driver lowering the signal or setting it to "Tariff 1" again from an intermediate position after he has begun to move it back.

When the signal is put back into the position shown in Fig. 1, the pin p^3 moves the lever p back, and this latter, through the medium of the pin q^2 , moves back the lever q^1 and flap q^3 , while the lever n^2 and tooth n are returned by the pin n^4 , so that all these parts are brought into the position shown in Fig. 1. The spring o^2 pulls the disk o^1 back

until it strikes the stop pin o^3 , so that the nose o^4 is returned into the position, shown in Fig. 1, under the arm p^1 . The setting of the flap q^3 by simply turning the knob o slightly can be performed with any tariff for which the apparatus is set, that is to say in the example illustrated with the apparatus either at "Tariff 1" or at "Tariff 2". Between the different tariffs the signal can thus, as already remarked, be moved to and fro at will. When once the flap q^3 has been displayed, it can only be moved out of sight by putting the apparatus to "Free". The setting to "Free" can only be done after the flap q^3 has been displayed. Thus the possibility of moving the signal to and fro to fraudulently alter the mechanism which checks the number of journeys is prevented. The passenger is not delayed either at the beginning or end of the journey by tedious manipulation of the apparatus by the driver, since at the beginning of the journey all that is necessary to set the apparatus is to lower the indicator e and at the end of the journey a slight turn of the knob o suffices to set the apparatus to "Cash".

Having thus described my invention, what I claim as new and desire to secure by Letters Patent is:—

- 30 1. In a taxameter or fare indicating apparatus for hired vehicles, in combination, a single hand-actuated device for setting the apparatus in operative condition, for setting the various tariffs or conditions of hire and for setting the apparatus out of operative condition, a special hand-actuated device for setting the apparatus at each tariff directly to "Cash", and a separate device, actuated by said latter device, indicating "Cash" separately from the tariff just set and simultaneously being exhibited, substantially as described.
- 35 2. In a taxameter or fare indicating apparatus for hired vehicles, in combination, a single hand-actuated device for setting the apparatus in operative condition, for setting the various tariffs or conditions of hire and for setting the apparatus out of operative condition, a hand-actuated device for setting the apparatus at each tariff directly to "Cash", a lever actuated by said device and fulcrumed on the casing, a "Cash" position indicating device released by said lever, clockwork-controlling means operated by said lever, and means for locking the first named setting device, said means being disengaged by said lever for the purpose of setting the apparatus out of operative condition, substantially as described.
- 40 3. In a taxameter or fare indicating apparatus for hired vehicles, in combination, a single hand-actuated device for setting the apparatus in operative condition, for setting the various tariffs or conditions of hire and

for setting the apparatus out of operative condition, a rotary handle, a cam connected with the handle, a lever fulcrumed on the casing and controlled by said cam, a "Cash" position indicating device released by said lever, clockwork-controlling means operated by said lever, means for locking the setting device, said means being disengaged by said lever, which lever is held in its locking position by said cam and released on turning said cam, substantially as described. 75

4. In a taxameter or fare indicating apparatus for hired vehicles, in combination, a device for setting the apparatus into and out of engagement; a rotary handle, a cam connected with the handle, a lever fulcrumed on the casing and controlled by said cam, a "Cash" position indicating device released by said lever, clockwork controlling means operated by said lever, means for locking the setting device, said means being disengaged by said lever, which lever is held in its locking position by said cam and released on turning said cam, substantially as described. 85

5. In a taxameter or fare indicating apparatus for hired vehicles, in combination, a hand-actuated signal device rotating in two directions, means, operated by said signal device, on the latter being rotated in one direction, for setting the apparatus to the various tariffs or working conditions, and for setting out of operative condition on rotation in the other direction, a disk connected with said signal, a double faced rack secured to said disk, a spring-actuated lever fulcrumed on the casing and either engaging with the two faces of the rack alternately to allow of rotation of the signal device in the two directions alternately, or held in its middle position to prevent backward rotation of the signal device, and a lever controlling said spring-actuated lever, and means for controlling said controlling-lever, substantially as described. 100

6. In a taxameter or fare indicating device for hired vehicles, the combination of a single-hand actuated device for setting the apparatus in operative condition and for setting the apparatus out of operative condition, locking means adapted to automatically render said device inoperative for setting the apparatus out of operative condition, a special hand-actuated device for setting the apparatus to "Cash", and means actuated by said special hand-actuated device for releasing said locking means. 115

7. In a taxameter or fare indicating device for hired vehicles, the combination of a single hand-actuated device for setting the apparatus in operative condition, for setting the various tariffs or conditions of hire, and for setting the apparatus out of operative condition, locking means adapted to automatically render said device inoperative for set- 120 125

ting the apparatus out of operative condition, a special hand-actuated device for setting the apparatus to "Cash", and means actuated by said special hand-actuated device for releasing said locking means.

8. In a taxameter or fare indicating apparatus for hired vehicles, a single hand-actuated device for setting the apparatus in operative condition, and for setting the apparatus out of operative condition, a special hand-actuated "Cash" indicating device, means for automatically locking said last mentioned device in indicating position, and means actuated by the first mentioned hand-actuated device for releasing said locking means and for moving said "Cash" indicating device out of indicating position.

9. In a taxameter or fare indicating apparatus for hired vehicles, a single hand-

actuated device for setting the apparatus in operative condition, for setting the various tariffs or conditions of hire, and for setting the apparatus out of operative condition, a special hand-actuated "Cash" indicating device, means for automatically locking said last mentioned device in indicating position, and means actuated by the first mentioned hand-actuated device for releasing said locking means and for moving said "Cash" indicating device out of indicating position.

In testimony whereof I have signed my name to this specification in the presence of two subscribing witnesses.

PAUL RICHERT.
